UNITED STATES PATENT OFFICE.

WILLIAM H. NICHOLS, OF WILKINSBURG, PENNSYLVANIA.

METHOD OF MOLDING.

Application filed November 1, 1922. Serial No. 598,360.

To all whom it may concern:

Be it known that I, WILLIAM H. NICHOLS, a citizen of the United States, and resident of Wilkinsburg, in the county of Allegheny and State of Pennsylvania, have invented a new and useful Improvement in Methods of Molding; and I do hereby declare the following to be a full, clear, and exact description thereof.

10 My invention relates to molds for forming the necks of rolls cast in groups or clusters, and for similar purposes, and it relates particularly to drag molds for use in casting clusters of rolling mill rolls.

15 The object of my invention is to provide an improved sand mold for simultaneously casting two articles having horizontal runners in line with each other and embedded in the sand. In preparing such a mold it

20 is a difficult matter to remove the patterns which form the runners. An important feature of my invention is the provision of a method of removing patterns from a mold of the kind described, this method consisting, in general, in providing an additional pattern which is removed after the mold is tamped and which gives access to the runner patterns. The opening or openings left by the additional pattern are then closed

25 by means of cores previously formed from molding sand or the like.

In my application for Letters Patent filed January 10, 1921, Serial No. 436,313, I have described and claimed a novel method 35 of casting chill rolls consisting in arranging a plurality of molds around a common upright pouring gate and pouring molten metal simultaneously through the upright gate into all of the molds. As shown in my prior application, the chills and the upright gate-box are all mounted upon a common drag flask in which the neck cavities, horizontal sprue-runners and the lower end of the upright pouring gate are molded in sand.

40 The present application is a continuation of my prior application No. 436,313, and is specifically concerned with the method by which the neck cavities, sprue runners and pouring gate are molded in the drag flask.

45 It will be understood that the principles of my present invention may be employed in making molds for other articles than rolling mill rolls and particularly in making

50 molds wherein two or more molding cavities

are connected by means of runners with a common pouring gate.

In the accompanying drawing, Fig. 1 is a vertical sectional view through a group of chill molds arranged for casting rolls according to my above-mentioned prior application, Serial No. 436,313, and provided with a drag mold constructed according to my present invention; Fig. 2 is a plan view of the drag flask and patterns; Fig. 3 is 65 a vertical sectional view of the drag flask and patterns shown in Fig. 2; Fig. 4 is a vertical sectional view similar to Fig. 3, showing the flask filled with sand and inverted preparatory to removing the patterns; Fig. 5 is another vertical sectional view similar to Figs. 3 and 4, showing the manner in which the sprue patterns are removed; Fig. 6 is another vertical sectional view similar to Figs. 3 to 5, showing the 70 final appearance of the mold after the patterns have been removed and the core blocks placed over the sprue runners; Fig. 7 is a plan view of the complete drag mold shown in section on Fig. 6; Fig. 8 is a detail plan 75 view showing the construction of the patterns used in molding the sprue runners; Fig. 9 is a detail plan view showing the core blocks which are placed over the inner portions of the sprue runners after the patterns 80 have been removed; and Fig. 10 is a detail view showing in vertical section the relation between the core blocks and the sprue runners.

In the drawing the numeral 2 indicates 85 a metal drag flask designed for casting four chill rolls. In order to receive the neck molds for the four rolls, the flask 2 is provided with four recesses 3 of generally circular form which communicate with a common central space through straight channels 5.

90 Fig. 8 shows a wooden pattern consisting of a four-armed member or cross 10 having a central projection 11 extending from one surface thereof. The pattern also includes four sprue patterns, each consisting of two sections 6 and 12, which are made separate 95 from the cross 10 and are adapted to be laid thereon when the pattern is assembled. Four neck patterns 13 are also provided for shaping the necks and couplers of the rolls, as shown in Fig. 3, each having a pin 14 adapted to enter the openings 9 in a follower-plate 7 which rests on the usual bumper, not shown.

In assembling the mold patterns, the flask 2 is placed in proper position on the follower plate 7, the cross 10 is set in the center of the flask, the sprue patterns 6 and 12 are then laid upon the arms of the pattern member 10, as shown in Figs. 3 and 8, and the neck patterns are placed in position at the ends of the sprue runners, with their pins 14 inserted in the openings 9. A little sand 10 should be placed under the projecting sprue patterns 12, as shown at 15, Fig. 3, in order to prevent these patterns from tipping over. Molding sand is then tamped into the flask in the usual manner, care being taken that 15 the sand shall be forced beneath the sprue patterns 12.

After the sand is tamped in the flask, the flask is inverted upon a suitable bottom plate 16, as shown in Fig. 4. The neck patterns 13 20 are then lifted out, and the four-armed pattern member 10 is also lifted from the sand. This leaves the sprue patterns still embedded for a portion of their length within the sand. In order to remove these sprue patterns the 25 inner pattern sections 6 are lifted, as shown in Fig. 5, leaving room for the outer sections 12 to be pulled lengthwise into the open space left by the four-armed pattern 10. The sections 12 are pulled horizontally one 30 by one in the manner stated, and are lifted sidewise and vertically from the mold.

The spaces originally occupied by the four arms of the pattern member 10 are then filled 35 with core blocks 17 previously molded from molding sand and of proper size to fit in these openings, and covering the sprue runners 18, as shown in Figs. 6, 7 and 10. The neck cavities 13 are then finished and coated in the usual manner, and the drag is ready 40 for use as shown in Fig. 2. When the drag is assembled with the chills and upright gate box, substantially all of the upper surface 45 of the sand is covered by these parts which prevent the sand from being forced up above the sprue runners during the pouring operation. The arms of the cross pattern 10 have their sides tapered slightly, as shown in Figs. 3, 4 and 10, in order that this pattern 50 may be readily lifted from the sand, and the sides of the core blocks 17 are similarly tapered.

Fig. 1 shows the complete assembly of the 55 group of chill molds, including the drag mold described above, chills 20, upper boxes 21, sink heads 22, and an upright gate box 23 to the upper end of which is secured a funnel 24. The vertical opening 25 in the upright gate box is in line with the central opening 26 in the upper surface of the drag mold, and the sprue runners 18, molded in 60 the manner described above, communicate radially with this central opening 26 and enter the neck cavities 13 tangentially in order to produce the proper swirling movement of 65 the metal.

In the operation of the mold shown in Fig. 1 to form a group of rolls, the molten metal is brought to the mold in a ladle and is poured into the funnel 24, whence it passes down through the upright channel 25 in the upright gate box 23 and through the horizontal sprue runners 18 into the lower portions of the molds. Some of the molten metal remains in the central cavity 26 and serves as a cushion to prevent the descending 70 metal from splashing.

It will be observed that the sides of the sprue runners 18 converge before entering the neck cavities of the molds. This gives a nozzle effect, causing the molten metal to be injected into the molds more forcibly than would be the case if the sprue runners were of uniform cross section throughout their length.

After the rolls are cast the chills and the upper boxes are removed and the cast rolls are lifted from the drag. Since there is nothing at this time above the sprue runners 18 except molding sand, the metal which has solidified in the horizontal runners is easily lifted from the drag, sometimes carrying with it the molding sand, and at other times breaking through the molding sand.

I claim as my invention:

1. The method of making a mold that comprises placing a pattern in a flask, laying a separate elongated pattern member upon said first-named pattern, filling said flask with sand, inverting said flask, removing said first-named pattern, and withdrawing said elongated pattern member by first moving said elongated pattern member lengthwise horizontally, and then lifting said member through the space left by said first-named pattern.

2. The method of making a mold that comprises placing a pattern in a flask, laying upon the said pattern a separate elongated pattern member narrower than said first-named pattern, filling said flask with sand, inverting said flask, removing said first-named pattern, withdrawing said elongated pattern member by first moving said pattern lengthwise horizontally and then lifting said member through the space left by said first-named pattern, and then placing a previously-formed block of molding material in the space left by said first-named pattern member.

3. The method of making a mold that comprises placing a pattern in a flask, laying a separate and elongated pattern member upon said first-named pattern with one end of said elongated pattern member projecting beyond said first-named pattern member, filling said flask with sand, inverting said flask, removing said first-named pattern, and withdrawing said elongated pattern member by first moving said

pattern member lengthwise horizontally and then lifting said member through the space left by said first-named pattern, and then placing a previously formed block of molding material in the space left by said first-named pattern member.

4. The method of making a mold that comprises placing a pattern in a flask, laying upon said pattern a separate elongated pattern composed of two members laid end to end, one of said members projecting beyond said first-named pattern, filling said flask with sand, inverting said flask, removing said first-named pattern, removing the inner section of said second pattern, and withdrawing the outer section of said second pattern by first moving said section lengthwise horizontally and then lifting said member through the space left by said first-named member, and then placing a previously formed block of molding material in the space left by said first-named pattern member.

5. The method of making a mold that comprises placing in a flask a pattern member having two oppositely extending arms and a central projection between said arms, laying upon the arms of said first-named pattern member elongated pattern members, each consisting of two sections laid end to end, filling said flask with sand, inverting said flask, removing said first-named pattern member, removing the inner sections of said elongated patterns, and removing the outer sections of said elongated patterns one by one, by first moving each outer section horizontally and then lifting it through the space left by said first-named pattern member.

40 6. The method of making a mold that comprises placing in a flask a pattern having four horizontal arms and a projection at the junction of said arms, placing upon

the horizontal arms of said pattern elongated pattern members each consisting of two sections laid end to end, the outer section of each of said elongated patterns projecting beyond the arm of said first-named pattern upon which it rests, filling said flask with sand, inverting said flask, removing said first-named pattern member, thus exposing the inner sections of said elongated patterns and portions of the outer sections thereof, removing said inner sections through the space left by said first-named pattern member, and then removing said outer sections one by one by first moving each section lengthwise horizontally, and then lifting said outer section vertically.

7. The method of making a drag mold for simultaneously casting a group of chill molds that comprises placing in a drag flask a pattern member having four horizontal arms symmetrically arranged around a central vertical projection, laying upon the arms of said first-named pattern member elongated sprue patterns, each consisting of two sections laid end to end, the outer ends of each outer section projecting beyond the ends of said pattern member, filling said drag flask with sand, inverting said flask, removing said four-armed pattern member, thereby exposing the inner sections and portions of the outer sections of said sprue patterns, lifting said inner sections out of the flask, and withdrawing the outer sections of the said sprue patterns one by one by first moving each outer section lengthwise and horizontally, and then lifting said section through the space left by said four-armed pattern member.

In testimony whereof, I, the said WILLIAM H. NICHOLS, have hereunto set my hand.

WILLIAM H. NICHOLS.
